UNITED STATES PATENT OFFICE.

JOHN H. TAYLOR, OF WATERLOO, NEBRASKA.

HORSE-COLLAR PAD.

No. 881,356.

Specification of Letters Patent. Patented March 10, 1908.

Application filed July 12, 1907. Serial No. 383,489.

To all whom it may concern:

Be it known that I, JOHN H. TAYLOR, a citizen of the United States, residing at Waterloo, in the county of Douglas and 5 State of Nebraska, have invented a new and useful Horse-Collar Pad, of which the following is a specification.

This invention relates to horse collar pads.

The object of the invention is to provide 10 a novel attachment of this character, that shall be positive in preventing any rubbing of the collar on the back of a horse's neck, that will readily assume different angular adjustments resulting from the movements 15 of the animal, and that may be easily and positively secured to the collar.

With the above and other objects in view as will appear as the nature of the invention is better understood, the same consists in 20 the novel construction and combination of parts of a horse collar pad as will be herein-after fully described and claimed.

In the accompanying drawings forming a part of this specification and in which like 25 characters of reference indicate corresponding parts,—Figure 1 is a view in vertical longitudinal section through the pad. Fig. 2 is a top plan view of the pad. Fig. 3 is a vertical transverse sectional view through the 30 pad. Fig. 4 is a perspective detail view of one of the pad members. Figs. 5 and 6 are detail views of slightly modified portions of the invention.

The attachment comprises a pad 1, which 35 may be constructed of any suitable material such as cast iron, or stamped sheet metal, and the inner face of which may be lined with zinc, or any other non-oxidizable metal or with felt or the like. As shown in Fig. 1 40 this pad is longitudinally bowed upward and is transversely curved in order to conform to the contour of the horse's neck and thus secure the greatest ease when worn.

Secured to the pad is a ball race 2 which is 45 provided on its under side with a plurality of pins or projections 3 that are adapted to be inserted through openings in the pad and to be upset, as shown at 4, thus to insure a stable connection between the parts. The 50 race incloses a plurality of balls 4^a that are disposed in a circumferential groove 5 in the bottom of the race and are engaged by a hemispherical boss 6 that is carried by a pad

bridge 7, which as shown in Fig. 1, is longitudinally and transversely curved in the 55 same manner as the pad. The bridge pad 7 is held assembled with the race by a socket 8, which latter is secured to the pad bridge by a plurality of bolts 9 that pass through ears 10 carried by the socket and are engaged 60 by nuts 11. Generally, it will be preferred to assemble the socket and pad bridge by means of bolts and nuts, as described, in order to permit of the parts being separated, if necessary; but if preferred rivets may be 65 employed in lieu of the bolts and nuts.

Carried by the upper face of the pad bridge are two inwardly-curved cleats 12 that are designed to engage with the collar to hold the attachment *a* assembled therewith. 70

When the attachment is assembled with the collar, the pad will readily adjust itself to the different positions assumed by an animal's neck, and all side thrusts will be obviated, thus insuring the greatest ease and comfort in use with the minimum wear and strain to the attachment. 75

Instead of employing the cleats 12 for holding the article assembled with the collar, cleats or bridges 13 may be employed for 80 this purpose, as shown in Figs. 5 and 6, and which will be held in position by the bolts 9 and nuts 11.

It will be understood that the invention is not to be limited to the precise details shown, 85 as in order to meet certain contingencies that might arise, changes in the construction of the different parts and the manner in which they are assembled may be resorted to when found necessary or expedient. 90

What is claimed is:—

1. An attachment of the class described, comprising a pad, a race secured thereto, ball bearings arranged in the race, a pad bridge carrying a hemispherical boss engaging the bearings, and a socket engaging the race and secured to the pad bridge. 95

2. An attachment of the class described, comprising a pad, a race rigidly secured thereto, ball bearings carried by the race, a pad bridge having a hemispherical boss engaging the bearings, a socket assembled with the race and secured to the pad bridge, and means carried by the bridge to secure the attachment to a collar. 100

3. An attachment of the class described,

comprising a pad, a race rigidly secured thereto, ball bearings within the race, a pad bridge having a hemispherical boss to engage the bearings, a socket encircling the race and 5 secured to the pad bridge, and inwardly-projecting cleats carried by the bridge to secure the attachment to a collar.

In testimony that I claim the foregoing as my own, I have hereto affixed my signature in the presence of two witnesses.

JOHN H. TAYLOR.
